UNITED STATES PATENT OFFICE.

NELSON CURTIS, OF BOSTON, MASSACHUSETTS.

STEAM-TANK VALVE.

SPECIFICATION forming part of Letters Patent No. 550,485, dated November 26, 1895.

Application filed June 17, 1892. Serial No. 437,022. (No model.)

To all whom it may concern:

Be it known that I, NELSON CURTIS, of Boston, Massachusetts, have invented an Improvement in Steam-Tank Valves, of which 5 the following is a specification.

The invention consists in the combination, with a steam-tank, a float, and a float-stem, of a valve-body outside of said steam-tank, provided with an inlet passage-way communicating with the interior of said tank, an outlet or discharge passage-way, a movable cap-head opposite said inlet passage-way, and a tubular valve fitting the interior of said valve-body between the said inlet and outlet passage-ways with a close fit, the said float-stem being secured to the valve and the said movable cap-head serving as the seat for the same.

The invention consists further in details of construction, more particularly in centering 20 the float-stem within the tubular valve and making a connection between said devices.

In the drawings, Figure 1 is a vertical section of a steam-trap embodying my said invention. Fig. 2 is a vertical section, upon an 25 enlarged scale, of the valve-body and valve shown at Fig. 1. Figs. 3 and 4 are modifications of the valve-body and valve, as herein-after more fully stated.

Except when otherwise stated, this description 30 refers more particularly to the valve-body, valve, and tank shown at Figs. 1 and 2. So far as may be, however, the same letters represent corresponding parts in all the figures; but in Figs. 3 and 4 numerals corresponding to said figures are added to the letters appropriated to the said parts.

T is the steam-tank. F is the float. A is the valve-body. V is the valve, being essentially a tube movable longitudinally in said 40 valve-body, its outer periphery closely fitting the inner periphery of said valve-body, as shown. The said valve V, near its end the more remote from the steam-tank, has an inward projection or cross-bar p, provided with a hole h, central to the said tube or valve V. R is the float-stem connecting the said valve with the float F, directly or indirectly, according to the location of the valve-body on the tank. In the position shown at Fig. 1, 45 where, as hereinafter described, the valve works horizontally, the float-stem R is in two

parts, the part lying within the tank being a pivoted bell-crank lever, the long arm of which is attached to the float.

The end of the float-stem R within the valve-body is secured to the projection p within the valve by a shouldered bolt B, passing through the hole h in said projection and screwing into the stem. The said inner end of the float-stem R is furnished with a feather or 55 feathers f to approximately center the rod in the tube or valve, and the said feathers are beveled, as shown, so that when the valve is slid into the valve-body the valve-stem readily enters the interior of the valve.

C is a cap serving as the head for the outer end of the valve-body and also as a seat for the valve. By unscrewing the cap-head C and the bolt B the seat, as well as the valve, may be removed for examination and grinding or 60 repairs. The valve-body A is provided with a pipe connection P, opening into an enlarged chamber c near the outer end of the valve-body. This pipe connection P furnishes the outlet o of the valve-body. The inlet i is at 65 the junction of the valve-body with the tank.

H is an ordinary pass-by valve.

In the position shown, Figs. 1 and 2, the valve V is on its seat, and communication between the tank and enlarged chamber c and 70 pipe connection P or outlet o is closed. When the float F rises, the valve V will be pulled back from its seat on cap C and communication will be opened from tank through inlet i, the interior of the valve V, and enlarged chamber c to outlet P.

In the modification shown at Fig. 3, A³ is the valve-body, V³ the valve, p³ the inward projection, R³ the float-stem, &c., as above stated; but the outlet to the enlarged chamber c³, instead of being through a pipe connection, is through a perforation o³ in the cap-head C³, and accordingly the valve-seat, instead of being upon the cap-head, is at the other end of the valve V³ upon a spider-plate 85 or a solid abutment D, near the inlet i³ of the valve-body, through which, however, the float-stem R works with a steam-tight fit. As shown, the valve V³ is supposed to work perpendicularly, the float-stem R³ being directly 90 attached to the float F within the tank.

At Fig. 4 the outlet o⁴ is through a pipe con-

nection P^4 , and the valve V^4 may be seated at either end—that is, upon the cap-head C^4 or upon the spider-plate or abutment D^4 , near the inlet end of the valve-body.

5 I claim—

1. The combination with the steam-tank T , float F , float-stem R , valve-body A provided with outlet passageway o , inlet passageway i opening out of said tank, and movable cap C ,
- 10 of tubular valve V , provided with inward projection p , and bolt B , screwing into said float-stem through, said projection, the said

tubular valve having its seat against said cap-head, substantially as described.

2. The combination with the steam-tank T , ¹⁵ float F , float-stem R provided with beveled feather or feathers f and valve-body A , of tubular valve V provided with inward projection p having central hole h , and the bolt B , substantially as described.

NELSON CURTIS.
